US00D665243S

(12) **United States Design Patent**
Yang

(10) **Patent No.:** **US D665,243 S**
(45) **Date of Patent:** **** Aug. 14, 2012**

(54) **SAFETY SECURING MECHANISM FOR SHEARS**

(76) Inventor: **Ching-Chen Yang**, Taichung (TW)

(**) Term: **14 Years**

(21) Appl. No.: **29/402,619**

(22) Filed: **Sep. 25, 2011**

(51) **LOC (9) Cl.** **08-05**

(52) **U.S. Cl.** **D8/107**

(58) **Field of Classification Search** **D8/107, D8/5, 52, 56, 106; 30/131, 132, 134, 155, 30/123.3, 124, 194, 199, 255, 262, 270, 266, 30/248, 252, 251, 154, 254, 160, 164; 81/418, 81/347; 16/430**

See application file for complete search history.

(57) **CLAIM**

The ornamental design for a safety securing mechanism for shears, as shown and described.

DESCRIPTION

FIG. 1 is a perspective view of a safety securing mechanism for shears showing my new design;

FIG. 2 is a front side view thereof;

FIG. 3 is a back side view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof illustrating usage thereof. The broken lines in FIG. 8 are for illustrative purposes only and form no part of the claimed design.
